UNITED STATES PATENT OFFICE.

ABRAHAM I. BLUM, OF NEW YORK, N. Y.

ADJUSTABLE HEADWEAR.

Application filed December 21, 1927. Serial No. 241,523.

This invention relates to adjustable headwear, and particularly to the means for adjusting the head sizes of caps. Said adjusting means is especially designed to eliminate 5 the extraneous fasteners, buckles, straps, elastic tapes and the like, which have heretofore been generally used for the purpose of making hats and caps adjustable.

My invention contemplates the provision 10 of simple, inexpensive and easily manipulated means for adjusting the head sizes of caps within a limited range of at least three sizes. Inasmuch as my invention is applicable to various types of headwear, it becomes 15 possible, with the use of my approved adjusting means, to apply the same to lined or unlined caps and to include in such adjustable headwear, a complete one-piece sweat band, in substantially the same manner as has here- 20 tofore been customary in headwear of the usual type which is not adjustable.

The various objects of my invention will be clear from the description which follows, and from the drawings, in which,

25 Fig. 1 is a partial vertical section and side view of a lined cap to which my invention has been applied, showing my improved adjusting means.

Fig. 2 is a similar view of a portion of a 30 cap embodying my invention, the thickness of the parts being greatly exaggerated for clear- ness, and the parts being shown in the positions assumed thereby when the cap is ad- justed to the largest head size possible.

35 Fig. 3 is a similar view of the same, show- ing the parts adjusted to give a smaller size.

Fig. 4 is a perspective view of a portion of the 40 adjusting flap, showing one form of the clamping means for maintaining the adjusting string in adjusted position.

Fig. 5 is a horizontal section of another 45 form of clamping means for the string.

Fig. 6 is a bottom plan view of an unlined cap to which my invention has been applied, 50 part of the sweat band being turned down to expose the adjusting flap and part being broken away to expose the string clamping means.

Fig. 7 is a front view of a part of the 55 adjusting band showing a modified form of opening therein for the passage of the string.

In the practical embodiment of my inven- 60 tion I prefer to use a tubular flap 10 of suit- able material, such as binding tape, which 65 flap is secured in place at or near the lower edge of the usual crown 11. Adjustment of

the size of the opening in the headpiece is ef- fected by swinging the flap 10 into various angular positions as will appear more fully hereinafter. It becomes possible, therefore, 60 to adjust the effective headsize of the head- piece in connection with either the lining it- self for the headpiece if the sweat band is omitted, or in connection with a sweat band, with or without a lining, while at the same 65 time using the crown of the conventional type without alteration of any kind.

Referring now to Figs. 1 to 6 inclusive, 70 wherein I have shown a cap to which my in- vention has been applied, it will be seen that the crown 11 and the visor 12 are of substan- tially conventional construction. When ap- plied to caps, I prefer to associate the adjust- 75 ing means with the comparatively narrow finishing flap which has sometimes been used to finish the lower edge of the crown. As 80 shown, the flap 10 comprises a piece of tape 13 folded to form a sort of tube and having the closed fold 14 at the inner or free periph- eral edge thereof, into the interior of which 85 flap the lower or terminal raw edge 15 of the crown is inserted and secured. For making the flap 10 comparatively stiff and resistant to deformation, I prefer to arrange inside there- 90 of a narrow piece of stiffening material 16, 85 made of buckram or the like, though it will be understood that if desired, the stiffening material may be omitted without materially affecting the proper functioning of the de- vice.

Referring now to Figs. 1 to 3 inclusive, 95 wherein a lined cap including a sweat band is shown, the sweat band 17 of the conventional type, is secured in place by seaming the lower edge 18 thereof to the inturned edge 15 of the crown, as by means of the stitching 19. The lining 20 may be secured in place to the outer 100 face 21 of the flap 10 by the same stitching 19, or by a separate line of stitching if desired, so that said flap 10 lies between the sweat band 17 and the lining and is normally hidden by the sweat band. It will be understood that the 105 space 22 is left in the interior of the flap 10 near the fold 14 thereof, into which an ad- justing device, such as the string or ribbon 23 110 may be inserted before the flap is finally se- cured in position. If desired, the tubular flap 10 may first be folded about the lower raw edge 15 of the crown and about the stiffening member 16 and seamed thereto and to the lower edge 24 of the lining 20 as by means of the stitching 25 before the sweat band 17

is secured in place. However, it will be seen that either the sweat band or the lining may be secured first to the flap 10, or both may be secured to said flap simultaneously if desired. 5 It will also be seen that the string 23 may be inserted in the space 22 before or after the flap is finished in its substantially tubular form.

Preferably at the front portion 26 of the 10 flap 10, a suitable opening 27 is provided, through which the ends 28 of the string 23 pass out of the interior of the said flap. The edge of said opening 27 is reinforced in any suitable manner, as for instance, by means 15 of an eyelet 29, or a button-hole as 30. After the ends 28 of the string have been tightened or loosened to the desired extent for adjusting the tension on the flap 10, said ends are prevented from entering the opening 27 any 20 further, by any suitable means adapted for that purpose. For example, I have shown in Fig. 1, the knot 49 made in the ends 28 of the string, which knot is large enough to prevent any part of the string from being drawn into 25 the inside of the flap, the knot being pulled into engagement with the edges of the opening 27 by the tension on the string. In Figs. 4 and 6 I have shown the ends 28 of the string passed through a fastener or clamp 50, after 30 which a knot 31 is made in said ends, so that the ends of the string are not lost into the interior of the flap 10, should the clamp become misplaced or loosened. Said clamp may consist of a base 32, and a hinge member 33, 35 pivotally mounted as at 34 on suitable flanges projecting from the base and provided with teeth 35 for pressing the string against the adjacent face of the base 32. Tensioning of the string 23 can thereby draw only that portion 40 of the string between the end of the clamp 50 and the opening 27, into interior of the flap, the clamp 50 and the string secured therein being prevented from passing through the opening 27 by the engagement of said 45 clamp with the edges of said opening. Referring to Fig. 5, I have there shown diagrammatically, a tapered clutch member 36, provided with an opening 37 through which are passed the ends 28 of the string, the clutch 50 being maintained in adjusted position on the string by any suitable means such as the ball 38. Said ball tends to jam the string on the attempted relative movement of the clutch and string in one direction, in a manner which is well known and which need not 55 be here described in any further detail.

If desired in any of the modifications shown, the flap may be secured at one point, preferably at the rear of the cap or hat, as at 60 44, to the sweat band so that both halves of the string beyond said point 44 pull equally on the tensioning thereof, and the danger of puckering the lower edge of the crown is avoided. It will be understood, however, that 65 the entire flap 10 may be free about its entire

periphery from the remainder of the headpiece except at the edge where it is hingedly secured in place.

In order to lessen the effective headsize of the headpiece the string ends 28 are pulled, thereby withdrawing part of the string through the opening 27 and out of the interior of the flap. The string is thereby shortened, the circumferential length thereof being lessened, thereby shortening the diameters of the inner or free edge of said flap. This operation causes the flap to swing inwardly toward the inside of the headpiece about the stitching 19 by means of which it is hingedly secured to the headpiece. The flap thereby is caused to assume a different angular position as illustrated in Figs. 1, 3 and 7. As clearly shown in Fig. 3, the tension on the string maintains the flap in its adjusted angular position, the string being prevented from lengthening under the tension by any of the means shown for that purpose, such as the knot 49, the clamp 50, the clutch 36, or any other suitable means. Where the sweatband 17 is used in the headpiece tensioning of the string and the consequent angular disposition of the flap 10, urges the lower part of the sweatband toward the inside of the headpiece (Fig. 3), by pushing inwardly against the sweatband, and distorting it somewhat from its normal shape, so that the sweatband can no longer stand up in its normal position comparatively straight as shown in Fig. 2, but is bent about the taut string, which makes an indent therein. The string thereby determines the effective headsize by its pressure against, and deformation of, the sweatband. It is obvious that it is the diameter of the tensioned string inside of the flap which determines the headsize, since the string must be of the proper diameter to pass about and fit the head in order that the headpiece may fit properly. It will also be seen that the string may be tensioned sufficiently to force the flap to lie in a plane for a minimum headsize, or to assume conical shapes of various altitudes for different headsizes. While it has been customary heretofore for the retailer to carry in stock, headpieces in each individual size for each style, it becomes possible with the use of my invention for the retailer to stock only a minimum number of sizes in each style. Adjustment within at least two or three sizes can easily be obtained by tightening or loosening the string or ribbon in the flap 10 as may be necessary, whereby it becomes possible for the retailer to quickly and easily adjust the headsize to the requirements of the individual customer. The adjusting means are normally hidden from view and do not in any way detract from the good appearance of the headpiece nor are the adjusting means subject to deterioration as are the elastic bands sometimes used for the same purpose. The various parts 125 130

of the adjusting device are inexpensive and are adapted to be quickly and easily assembled at minimum expense. The adjusting device, being entirely independent of the crown, 5 cannot wrinkle or pucker up the crown, nor is it necessary to slit or separate the parts of the crown at any point. It will be seen therefore, that the headpiece provided with my improved adjusting means presents in all respects the same appearance as that of the conventional headpiece, and that the adjustment 10 can be efficiently effected within a limited range of sizes by pushing upon the sweatband or the lining as the case may be to 15 change the size thereof.

It will be understood that various changes in the construction shown and described may be made such as in the type of clamp used for maintaining the adjustment of the string, in 20 the proportions and arrangement of the flap, in the lining, and other changes which are contemplated and which fall within the spirit and scope of this invention. It is therefore intended to claim the invention as broadly 25 as is permitted by the state of the prior art and the terms of the appended claims.

I claim:

1. In an adjustable cap, a fabric crown, an inturned lower edge on the crown, a sweatband secured at its lower edge to said crown, 30 a continuous tubular flap of comparatively thin and soft material, having an opening interposed between the sweatband and the crown and secured thereto about the lower edge of the cap and enclosing said inturned 35 edge, said flap being of less height than that of the sweatband and normally concealed thereby, a string, arranged in the upper part of said flap, ends on said string passing out 40 through said opening into the interior of the cap, and fastening means slidable on the ends of said string and in the interior of the cap, 45 said fastening means being adapted to be covered by said sweatband.

2. In an adjustable cap, a crown of the conventional type, an inturned lower edge on 50 said crown, a tubular flap of soft, flexible material secured to and hinged about the lower edge of said crown, part of said lower edge entering thereinto, said flap having an open-

ing therein, and serving as a finishing covering for the inturned lower edge of the crown and as a pocket for an adjusting member, an inelastic adjusting member arranged in the upper portion of said flap and having its 55 ends passing out through said opening, whereby the effective length of said string may be varied, and means for maintaining the effective length of said string including a fastening device movable on the ends of 60 the string for connecting said ends.

3. In an adjustable cap, a crown of the conventional type, an inturned, upwardly bent lower edge on the crown, a strip of comparatively soft material secured about and enclosing 65 the lower edge of the crown for finishing said crown and providing a pocket hinged to said crown, and an inelastic member in said pocket and emerging therefrom into the interior of the cap, for adjusting the position of 70 said pocket.

4. In an adjustable cap, a crown of the conventional type, a member secured about and enclosing the lower edge of the crown providing a stiffened pocket hinged to said 75 crown, an elongated inelastic member in said pocket emerging therefrom into the interior of the cap, means on said elongated member outside of said pocket for connecting the ends of the member and for adjusting the effective 80 length thereof and preventing the retraction of said member into the pocket under tension, and a complete one-piece sweatband normally covering said pocket member while allowing 85 access thereto.

5. In an adjustable cap, a crown of the conventional type, a pocket forming flap member hinged to and arranged about and enclosing the lower edge of the crown, said member having an opening therein, an inelastic member arranged inside of and at the top of said flap member and having its ends passing through said opening into the interior of the cap, adjustable connective means on the ends 90 of said inelastic member, a lining for said cap secured on the side of said flap member adjacent the crown, and a complete one-piece sweatband secured to the crown below the flap member.

ABRAHAM I. BLUM.
